L. R. COLBERT.
AUTOMOBILE DOOR.
APPLICATION FILED APR. 8, 1911.

Patented Apr. 9, 1912.

UNITED STATES PATENT OFFICE.

LUCIAN R. COLBERT, OF MASSAPONAX, VIRGINIA.

AUTOMOBILE-DOOR.

1,023,007.

Specification of Letters Patent.

Patented Apr. 9, 1912.

Application filed April 8, 1911. Serial No. 619,883.

To all whom it may concern:

Be it known that I, LUCIAN R. COLBERT, a citizen of the United States, residing at Massaponax, in the county of Spotsylvania 5 and State of Virginia, have invented a new and useful Automobile-Door, of which the following is a specification.

It is the object of the present invention, to provide a supporting structure, whereby 10 a screen may be held upon the door of an automobile or other vehicle, the supporting structure being so constructed that it may be telescoped within the door, and hidden from view when not in use.

15 With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

20 In the drawings, —Figure 1 is a side elevation of a vehicle equipped with the device of my invention; Fig. 2 is a vertical transverse section of a portion of one door of the vehicle, showing the support of my invention mounted therein, the support being extended. Fig. 3 is a similar view showing the support telescoped, and housed within the contour of the door; Fig. 4 is a horizontal transverse section upon the line A—B 25 of Fig. 2; Fig. 5 is a detail perspective of the lower guide member; and Fig. 6 is a fragmental detail, in elevation, enlarged from Fig. 1, and designed to show one form of the longitudinally extensible cross bar 30 which unites the supports which are carried by the front door of the vehicle. Fig. 7 is a perspective of the top guide.

In the drawings, the body of the vehicle is denoted by the numeral 1, the top being 35 denoted by the numeral 2. The sides of the vehicle, between the body 1 and the top 2 are suitably housed in by a screen 3.

The rear door is denoted by the numeral 4, and the front door by the numeral 5.

40 The panels of the door are denoted by the numeral 6, the bottom of the door by the numeral 7. The upper edge of the door is closed by a movable lid 8, the same being preferably, although not necessarily, hingedly connected with the door.

The foregoing description applies with equal propriety to both the rear door 4 and the front door 5.

In each door, adjacent the vertical edges thereof, longitudinally extensible, telescopically constructed screen supports are mounted. These screen supports are identical in construction, and but one of them will be described, it being understood without further comment, that the description applies 65 with equal propriety to the other support which is mounted in each door.

Secured between the panels 6, adjacent the upper edge of the door 4, is a guide 9 having a central opening 9^a with one or more peripheral slots 9^b. Below the guide 9 is located another guide 10, seen most clearly in Fig. 5. This guide 10, preferably, although not necessarily, is in the form of a washer, having a central circular opening 70 75 12. In the upper face of the guide 10, about the periphery of the opening 11, are spaced seats 12, terminating, at their lower ends, within the contour of the guide. Located at a distance from the seats 12, are slots 14, extended downwardly, entirely 80 through the guide 10, the slots 14 opening into the circular aperture 11.

The telescopic, longitudinally extensible 85 supporting member includes, as a primary element, a tube 15, adapted to fit closely in the opening 11 of the guide 10, and to slide in the opening 9^a of the guide 9. The tube 15 is equipped with outstanding lugs 16, adapted 90 to fit in the seats 12 in the guide 10, so as to uphold the tube. In order to maintain the lugs 16 engaged with the seats 12, a spring 17 is secured to the under face of the upper guide 9, this spring being adapted to bear against the upper end of one of the lugs 16, as clearly shown in Fig. 2.

95 Slidably mounted within the tube 15, is another tube 18. The tube 18 is maintained in fixed relation with respect to the tube 15, by means of a spring latch 19, secured to the tube 15, and adapted to extend through an opening therein, to engage with the tube 18. Slidably mounted within the tube 18, is a rod 20. There is a spring latch 100 21 upon the tube 18, adapted to engage the rod 20, after the manner of the element 19. In the upper end of the tube 15, a slot 22 is fastened, adapted to receive the latch 21, under certain circumstances which will be 105 described hereinafter. The upper ends of 110

the rods 29 which are located along opposite edges of the door, are connected by a cross bar 23.

The construction above described, and applied specifically to the rear door 4, applies with equal propriety to the forward door 5, with the following exception. The rods 24, in the case of the forward door 5, these rods 24 supplanting the rods 20, are connected 10 by a longitudinally extensible cross bar, as shown in Fig. 6. This cross bar preferably consists of two parts 25 and 26, one of which is telescoped within the other, the parts 25 and 26 being pivoted, as shown at 15 27, to the rods 24. The reason for providing the telescoping parts 25 and 26 is that when the rods 24 are elevated, the parts 25 and 26 are adapted to lie, in diagonally disposed position, against the brace 28, which 20 upholds the cover 2, as shown in Fig. 1. If the rods 24 are to be slid downwardly, so as 25 to be housed within the body 1, the connection between the upper ends of the rod 24, obviously, must yield longitudinally. One 30 of the slots 9^b in the guide 9 serves to receive the latch 19 when the device is telescoped. A screen 29 is removably connected with the members 15, 18 and 20 upon one side of the door, and with the corresponding members 35 upon the other side of the door, this screen being united with the cross bar 23 in the case of the rear door, and with the parts 25 and 26 in the case of the front door.

The operation of the device, presupposing 35 that the parts are positioned as shown in Fig. 2, is as follows. The screen 29 is first removed, and the latch member 21 is manipulated, to permit the rod 20 to slide within the tube 18, the latch 19 being manipulated 40 later to permit the tube 18 to slide within the tube 15. The latch 21 will register in the slot 22. By rotating the tube 15, the same having been first elevated, to permit the lugs 16 to move out of the seats 12, the 45 lugs 16 may be slid downwardly through the slots 14 in the lower guide 10. Under such circumstances, as shown in Fig. 3, the support will be disposed in telescoped position, and be housed completely beneath the 50 lid 8 of the door, there being a sufficient space, between the upper guide 9 and the lid 8 to accommodate the cross bar 23 in the one instance, and the cross bar comprising the parts 25 and 26 in the other instance, it

being noted that a telescoping is necessary, 55 between the parts 25 and 26 in order that the same may be housed beneath the lid 8, in the case of the forward door 5.

From the foregoing it will be seen that an efficient structure is provided, whereby 60 screens may be applied to the doors of a vehicle, the construction being such that when the occasion for the use of the supports has passed, the same may readily be housed within the contour of the door, in an out-of-the-way position, so as to detract nothing 65 from the general appearance of the vehicle upon which the device is mounted.

Having thus described the invention, 70 what is claimed is:—

1. The combination with the door of a vehicle, of spaced telescoped supports slidable vertically on the door; and a longitudinally extensible member terminally pivoted to the supports. 75

2. The combination with the door of a vehicle, of a longitudinally extensible support provided at its upper extremity with an angularly disposed longitudinally extensible supporting member; the support and the 80 supporting member being movable within the contour of the door.

3. The combination with the door of a vehicle, of spaced guides thereon, one of which is provided with seats, and with slots extended entirely through said guide; a supporting member slidable in the guides and having a lug adapted to register in the seats, and to pass through the slots when the support is rotated to dispose the lug out of seat-engaging position; and a spring upon the other guide, adapted to bear against the lug, to maintain the same in the seat. 85

4. In a device of the class described, parallel members; a longitudinally extensible connection pivotally united adjacent its ends with said members, adjacent the upper ends of said members; and means for securing said members to the door of a vehicle, for vertical sliding movement. 90

In testimony that I claim the foregoing as my own, I have hereto affixed my signature in the presence of two witnesses.

LUCIAN R. COLBERT.
